CALCULATING MACHINE

George C. Chase, South Orange, N. J., assignor
to Monroe Calculating Machine Company,
Orange, N. J., a corporation of Delaware

Application November 8, 1935, Serial No. 48,810

6 Claims. (Cl. 235—75)

The invention relates to calculating machines and more particularly to means for using the "two table" multiplier, described in Patent No. 1,842,584 issued January 26, 1932 to George C. Chase, with the newly discovered principle of inverted registration described in co-pending application of George C. Chase filed January 23, 1935 Serial No. 3,091.

The system of inverted registration comprises the registration of the digital complement of a selected value, in combination with an inverted tens transfer action wherein a transfer will occur only when the lower order numeral wheel fails to pass from 9 to 0 or from 0 to 9 or, in other words, through $9\frac{1}{2}$ registering position.

As fully described in connection with the modified form of the invention disclosed in application No. 3,091, semi-inversion of additive or subtractive calculations provides for a maximum of five steps in registering any of the digits 1 to 9, the digits 5 to 9 being registered complementally and the digits 1 to 4 normally both in addition and subtraction, some of the numeral wheels rotating forwardly and others reversely during the same cycle of operation.

While the present invention is shown as applied to this semi-inverted form of the application, it is of course evident that it is applicable to the fully inverted system.

The invention consists in the novel construction and combination of parts, as set forth in the appended claims.

In the accompanying drawings, illustrating the invention:

Fig. 1 is a right hand side elevation (with parts broken away and shown in section) of a calculating machine embodying the invention.

Fig. 2 is a right hand elevation of the multiplier control mechanism.

Fig. 3 is a detail view of the driving gearing for the pair of cylinders.

Fig. 4 is a diagrammatic projection of a pair of actuator cylinders in normal relative position.

Fig. 5 is a similar view, with the cylinders in $2\times$ position.

Fig. 6 is a front elevation of the machine with parts broken away.

Figs. 7, 8 and 9 are detail views of the tens transfer mechanism.

For the sake of simplicity the invention is herein shown as applied to a calculating machine of the well known Thomas type, as illustrated, for example in the British patent to Samuel Tate, No. 27,364 of 1903. Obviously the invention

might be readily applied to machines of totally different construction.

In the drawings actuator cylinders 70 and 71 correspond to the plus and minus cylinders 70, 71 of the aforementioned application Serial No. 3,091, but are arranged and provided with groups of teeth in the following manner:

In each of the columns plus cylinder 70 is slidably mounted on square shaft 72, driven by bevel gearing 73 from the drive shaft 74. Minus cylinder 71 is slidably mounted on a square shaft 95 suitably supported in the framing above cylinder 70. Gear connections 75 serve to drive cylinders 71 in opposite direction to the cylinders 70.

Each of the cylinders 70, 71 is provided with two sets of teeth 96, 97, the teeth 96 of cylinders 70 being adapted to register the normal digits 1 to 4 and the corresponding teeth 96 of cylinder 71 the inverted digits 5 to 9.

The teeth 97 of cylinders 70 are adapted to register normally the products of 1×2 and 2×2 , namely 2 and 4, also the units of the products of 6×2 and 7×2 , namely 2 and 4, and the corresponding teeth 97 of cylinder 71 to register complementally the products of 3×2 and 4×2 , as 4 and 2, also the units of products of 8×2 and 9×2 as 4 and 2. The product, 10, of 5×2 calls for no teeth on the cylinders 70 and 71, this value, together with the tens of the higher products being registered by other means to be described later.

1 $\times$ multiplier

An actuator pinion 78, rotatably fixed to and slidably upon a shaft 81, is normally adapted to be brought into mesh with any of the series of teeth 96 of cylinders 70, 71 by graduated adjustment along the face of the cylinders by means of a slide 91, extending up through the cover plate and provided with a button 92. The teeth 96 are so arranged that movement of the actuator pinion 78 from rear to front of the machine will bring said pinion into co-operative position with 1, 2, 3, 4 teeth of the forwardly rotating cylinder 70 and with 5, 4, 3, 2, 1 teeth of the reversely rotating cylinder 71, progressively.

Opposed bevel gears 79, 80 are fixed upon a sleeve slidably mounted upon the squared shaft 50 81, upon which the actuator pinion 78 is also mounted, these bevel gears being shiftable to engage alternatively with the bevel gear 82 attached to the numeral wheel 83. This shifting movement is accomplished by means of a

slidable bar 84 located between the gears 19 and 80, and adjustable by a change lever (not shown) in the manner well known in Thomas type calculating machines.

5 With the bevel gear 19 engaged with gear 82, the wheel 83 will be rotated additively if the pinion 78 is engaged by the teeth of cylinder 70, and subtractively by the engagement of the teeth of cylinder 71. On the other hand, when 10 the gear 80 is engaged with gear 82, the effect of the cylinders 70, 71 upon the wheel 83 is reversed, cylinder 70 acting subtractively and cylinder 71 additively.

With the machine set for normal or 1 table 15 operation, multiplication is performed by the registration of repeated additions, and division by the registration of repeated subtractions.

Normally, as a numeral wheel registration passes from 9 to 0, 10 will be registered on the 20 next higher numeral wheel 83, by the action of a tooth 21 of the lower order wheel acting upon levers 22 and 23, in a manner hereinafter more fully described, lever 23 acting to slide a tooth 24 rearwardly upon the shaft 72 of the higher order 25 wheel. The hub of tooth 24 rotates with the shaft 72 and after the teeth of cylinders 70, 71 have completed their action, this tooth 24 will pass through the teeth of tens transfer pinion 85, slidably mounted upon the shaft 81.

30 Since the entire drive to the numeral wheels 83 is reversed by the adjustment of the bar 84 no special reversing means for the tens transfer is necessary.

The cylinders 70, 71, and the teeth 24 on the 35 series of shafts 72, are mounted in varying angular positions, so that the teeth 24 will act successively from right to left of the machine, in well known manner.

Tens transfer inversion

40 The following means are provided to invert a tens transfer whenever setting knob 92 stands in position corresponding to a selected value from 5 to 9.

45 As the setting knob 92 is moved from 4 to 5 position, an anti-friction roller 90, secured to slide 91, will engage the surface 89 of an arm 86, pivotally mounted upon a rod 88 extending transversely of the machine, as shown. A projection 98 of arm 86 normally overlies the roller 99, carried on the upper end of an arm 100, pivotally mounted at 101 upon lever 102. Lever 102 is fulcrumed upon a support rod 103 and has a yoke engaging carry pinion 85 of the next higher 55 order column.

Engagement of roller 90 therefore with surface 89 of arm 86 will cause said arm to be rocked downwardly about point 88, whereupon projection 98 acting against roller 99 will depress arm 100, rocking the lever 102 counter-clockwise about its fulcrum 103, to bring the pinion 85 into the path of movement of the related tens transfer tooth 24. If however a lower order dial 83 passes through 9½ position, the tooth 21 of said dial 65 will rock the lever 22, forcing the tooth 54 of lever 23 (Fig. 8) into one of the shallow notches 58 of lever 22, to move the tooth 24 out of the plane of gear 85, inverting the transfer as described in application Serial No. 3,091.

70 At the end of each cycle of operation, the tens transfer parts are restored to normal position by means of cam teeth 59 (Fig. 9), mounted upon the shafts 72, which engage the fingers 60 of restoring levers 61, loosely mounted upon the 75 shafts 81 and provided with upward extensions

engaging perforations of the levers 22, to move said levers into centralized position, with the deep notches 55 thereof opposite the teeth 54 of levers 23.

2 × multiplier

5

In order to register the partial products of a 2 × multiplier a settable key 104 is provided. This key extends through the keyboard and is pivoted at its lower end on bell crank lever 105, 10 fulcrumed upon a stud 106, fixed in the left hand framing of the machine. Secured in the upper and lower arms of lever 105 are transversely extending rods 107, 108 supported similarly from the right hand framing of the machine. 15

Rods 107, 108 engage suitable channels of the plus and minus cylinders 70, 71, so that, upon depression of the (2 ×) key 104, cylinder 70 will be pushed a half step rearwardly and cylinder 71 will be drawn a half step forwardly along their 20 shafts.

The above described movement of cylinders 70, 71 is adapted to move the (1 ×) multiplier teeth 96 out of cooperative relation with actuator pinion 78, in its graduated positions of adjustment, and to move the (2 ×) multiplier teeth 97 into cooperative relation with said pinion. 25

It will be noted from an inspection of Figure 5 that there are four series of four teeth 97 each 30 and four series of two teeth. Two of each of these series is located on the forwardly rotating cylinder 70 and two series on the reversely rotating register 71. The series represent the units of the products of digits 1—9, multiplied by 2. 35

Tens transfer inversion

Depression of the (2 ×) key will also, in the following manner, provide for a transfer inversion whenever a selector button 92 stands at the 3, 4, 8 40 or 9 position.

For each column of the machine there is pivotally secured to the rod 107 a link 109 having pivotal connection at 110 with the arm 100, and as key 104 is depressed, rocking bell crank 105, link 109 will rock arm 100 forwardly, to bring the roller 99 from beneath the projection 98 of lever 86 and under the projection 111 of an arm 112, similar to the arm 86, and pivotally mounted upon shaft 88. Arm 112 is provided with cam elevations 113, 114, adapted as roller 90 is moved to the 3—4 or 8—9 setting position to cause said arm to be depressed and held in depressed position. 45

Depression of arm 112 will cause projection 111, acting through roller 99, arm 100 and lever 102, to slide the carry pinion 85 into active position relative to tooth 24, to invert the tens transfer as previously described. 50

Provision is made, as described in application Serial No. 3,091, for setting and unsetting a tens transfer if the numeral wheel moves twice through the 9½ position during a single cycle of operation, because of a registering movement being followed by a transfer movement of opposite sign. 60

Partial product tens

Special means are provided to register the tens of the partial products 10, 12, 14, 16 and 18, comprising for each order a link 115, pivotally secured at the forward end thereof to the shaft 107 70 and at its rearward end to an arm 116. Arm 116 is pivotally mounted upon a lever 117, fulcrumed upon shaft 103, said lever having a yoke engaging the grooved hub of gear 118, slidably mounted upon square shaft 81 of the next higher order. 75

Upon depression of key 104 link 115 will rock arm 116 to bring a roller 119, secured in the upper end of said arm, beneath projection 98 of arm 86 so that as setting button 92 is moved to 5-9 position, roller 90 will depress arm 86 and projection 98, acting through roller 119, arm 116 and lever 117 will slide the gear 118 into the path of movement of a tooth 120, formed integrally with the plus cylinder 70, said tooth having been moved 10 a half step toward pinion 18 during the rearward movement of the cylinders 70 previously described.

Tens product tooth 120 is timed to act immediately before the teeth 97 of the related cylinder 70. Since however there is a maximum of only 15 four teeth in the $2 \times$ table, the action of tooth 120 may coincide with that of the first tooth of the $1 \times$ table.

Key 104 is latched down during a cycle of operation by engagement of projection 121 of said key with the underside of the keyboard plate. Automatic key release means, such as described in reference Patent No. 1,842,584, may of course be provided, adapted to release key 104 only after the completion of the cycle in which the operator 25 releases said key.

Overthrow of the parts is prevented, and the accurate location of these parts in normal position is effected by means of check springs 52, operating between the teeth of start wheels 53, 30 fixed upon shafts 81.

Operation

Taking the illustrative problem—

$$35 \quad 7328 \times 7 = 51296$$

and assuming all the buttons 92 and dials 83 to be standing at 0 and the change lever to be set for addition, holding the slide 84 in the position shown in Fig. 1, wherein adding gear 79 is in mesh 40 with dial gear 82:

The right hand or units button 92 is pulled forwardly to a point on its scale indicating 8. This brings the related actuator pinion 78 into position to be meshed by two of the teeth 96 of the cylinder 71, and also, through the roller 90 and lever 86, moves the tens transfer pinion 85 in the next column forwardly, into position to be meshed by the tens transfer tooth 24.

The button 92 in the second or tens column is 50 pulled down to a registration of 2, bringing the related actuator pinion 78 opposite two of the teeth 96 of the cylinder 70, and leaving the related tens transfer pinion 85 out of line with the tens transfer tooth 24. In the third column the 55 button 92 is adjusted to the 3 position, providing for the registration of three of the teeth 96 of cylinder 70 and leaving the transfer pinion 85 out of line with the transfer tooth. In the fourth column the button is drawn down to the 7 registering position, pinion 78 being opposite three teeth 96 of the cylinder 71, and transfer pinion 85 being brought into line with the transfer tooth 24.

In the above described position of the parts a single rotation of shaft 74 would rotate the cylinders 70 additively and cylinders 71 reversely, to register the value 7328 upon the product dials 83 in the manner described in the aforementioned application Serial No. 3,091, the digits 2 and 3 of the tens and hundreds column being registered 65 normally and the digits 8 and 7 of the units and thousands columns being registered as -2 and -3. In this condition of the machine seven cycles would be required to register the product 51,296 of 70 7328×7 .

75 Use of the $2 \times$ key 104 however will provide for

a four cycle operation to register said product, in the following manner:

As previously stated, depression of key 104 will slide cylinders 70 a half step rearwardly and cylinders 71 a half step forwardly. Thus in the 5 units column four teeth 97 of cylinder 71 will be moved into cooperation with the pinion 78, to register upon a single cycle of operation the complementary units partial product (4) of 8×2 , in the tens column four teeth 97 of cylinder 70 will be 10 moved into relation with pinion 78, to register the normal product (4) of 2×2 , in the hundreds column four teeth 97 of cylinder 71 will be moved into relation with pinion 78, to register the complementary product (4) of 3×2 , and in the thousands column four teeth 97 of cylinder 70 will be 15 moved into relation with pinion 78 to register the normal units partial product (4) of 7×2 .

The tens of the product 8×2 of the units column and of 7×2 in the thousands column will be 20 registered because depression of key 104 has rocked the rollers 119 of arms 116 beneath the projections 98 of arms 86, said arms being held in depressed position by roller 90 of the units and thousands column buttons 92, to bring the 25 tens tooth 120 of the related order into cooperation with the higher order gear 118.

Since registration of the values 6-9 calls for a tens transfer inversion, it will be apparent that in the units and hundreds columns, the roller 90 30 will engage projections 114 and 113 of the related arms 112 and depress said arms whereupon, roller 99 being beneath the projections 111, transfer pinions 85 of the next higher orders will be moved into cooperative position relative to their respective teeth 24. In both these columns 4 is subtracted from 0, the numeral wheels passing from 0 to 9 and teeth 21, acting through levers 22 and 23, will act to unset the transfer, as previously 35 described.

In the tens and thousands columns, the setting buttons 92 having been set at the 2 and 7 positions respectively, roller 90 of said keys will be opposite the low portions of arms 112 and the pinions 85 in these columns will be left out of 45 plane with their related teeth 24. In these columns the related numeral wheels 83 will not pass from 9 to 0, and again no transfer will occur.

As a result of the operation above described the numeral wheels 83 will register 14,656, the 50 product of 7328×2 . The calculation will be completed thus:

$$\begin{array}{r}
 14,656 \\
 14,656 \\
 14,656 \\
 7,328 \\
 \hline
 51,296
 \end{array}
 \quad 55$$

To register the product 7328×7 , therefore, 60 three cycles of operation would first be performed with the $2 \times$ key in depressed position (registering the product of six times 7328) and one cycle of operation with said key in raised position.

I claim:

1. In a calculating machine having numeral wheels; digit selector devices, actuators including elements settable by said devices and cooperating elements adapted to register on said numeral wheels the selected values and complements thereof or alternatively to register products of such values and complements thereof, cooperating tens product gearing, normally disabled means for setting the tens product gearing to and from operative position in accordance with the 75

setting of the selector devices, means settable to adjust the cooperating actuator elements from selected value to product registering condition, and means connected with the last named means and settable therewith to enable the normally dis-
5 abled setting means.

2. In a calculating machine having numeral wheels, digit selector devices, actuators including elements settable by said devices and cooperating elements adapted to register on said numeral wheels the selected values and complements thereof or alternatively to register products of such values and complements thereof, cooperating tens product gearing including slidably mounted pin-
10 ions, shifting levers engaging said pinions, arms pivotally connected to said levers, control levers adjustable by the selector devices in selecting a higher digit value, a lever settable to adjust the cooperating actuator elements from selected value
15 to product registering condition, and a link connection between the last-named lever and the pivoted arms and adapted to bring the arms into the path of movement of the control levers.

3. In a calculating machine having numeral wheels, the combination with tens transfer devices between said wheels including elements settable by the lower order wheels and means adjustable to invert the operative and inoperative effect of said elements in their relatively set positions; of digit selector devices, actuators includ-
25 ing elements settable by said devices and cooperating elements adapted to register on said numeral wheels the selected values and complements thereof or alternatively to register products
30 of such values and complements thereof, cooper-
35 ating normally inactive tens product gearing, control devices adjustable by the selector devices in selecting a higher digit value, and means settable to connect the control devices with the in-
40 verting means or alternatively with the tens product gearing.

4. In a calculating machine having numeral wheels, the combination with tens transfer devices between said wheels including elements settable by the lower order wheels and means in-
45 cluding slidably mounted pinions adjustable to invert the operative and inoperative effect of said elements in their relatively set positions, shifting levers engaging said pinions, and arms pivotally connected to said levers; of digit selector devices, actuators including elements settable by said devices and cooperating elements adapted to register on said numeral wheels the selected
50 values and complements thereof or alternatively to register products of such values and comple-
55 ments thereof, cooperating tens product gearing

including slidably mounted pinions, shifting levers engaging said pinions, arms pivotally connected to said levers, control levers adjustable by the selector devices in selecting a higher digit value, and a lever connected with and operable
5 to set the inversion setting arms or alternatively the tens product setting arms into the path of movement of the control levers.

5. In a calculating machine having numeral wheels, the combination with tens transfer de-
10 vices between said wheels including elements settable by the lower order wheels and means ad-
justable to invert the operative and inoperative effect of said elements in their relatively set posi-
15 tions; of digit selector devices, actuators includ-
15 ing primary elements settable by said devices and cooperating elements adapted to register on said numeral wheels the selected values and comple-
20 ments thereof or alternatively to register products of such values and complements there-
of, two control devices each differentially adjust-
25 able by the selector devices in accordance with setting of the primary actuator elements to reg-
30 ister a selected value or a complement, means settable to adjust the cooperating actuator ele-
35 ments for selected value or alternatively for product registration, and means connected with the last named means and settable therewith for operation by one or by the other of the control devices to adjust the inverting means.

6. In a calculating machine having numeral wheels, the combination with tens transfer de-
35 vices between said wheels including each an ele-
ment settable by the lower order wheel, and means including a slidably mounted pinion ad-
justable to invert the operative and inoperative effect of said element in its relatively set position, a shifting lever engaging said pinion, and an arm pivotally connected to said lever; of digit selector devices, actuators including elements
40 settable by said devices and cooperating ele-
45 ments adapted to register on said numeral wheels the selected values and complements thereof or alternatively to register products of such values and complements thereof, two control levers each
50 adjustable by the selector devices in the selection of different given digit values, a lever settable to adjust the cooperating actuator elements for selected value or alternatively for product regis-
55 tration, and a link connection between the last-
named lever and the pivoted arm and adapted to bring the arm into the path of movement of one or alternatively of the other of said control levers.

GEORGE C. CHASE. 55
